CARBURETOR CONSTRUCTION

Olin J. Eickmann, Normandy, Mo., assignor, by mesne assignments, to ACF Industries, Incorporated, New York, N.Y., a corporation of New Jersey

Application September 29, 1955, Serial No. 537,335

3 Claims. (Cl. 261—34)

This invention relates to carburetors and, more specifically, to a carburetor which features a novel arrangement of its elements, permitting a simplified construction, few parts, and a compact design.

The actual carburetor described hereinafter is only four inches high, and is illustrated in full scale in the accompanying drawings, in which:

Fig. 1 is a top plan view with parts broken away and in section to reveal details of the construction.

Fig. 2 is an elevation in section taken on the line 2—2 of Fig. 1.

Fig. 3 is a side elevation in section taken on a center line of Fig. 1.

Fig. 4 is a side elevation of Fig. 1 with parts broken away to illustrate details of construction.

Fig. 5 is a top plan view with the cover removed.

Fuel bowl and float structure

According to this invention, the carburetor, generally indicated as C is divided into two main sections. To facilitate manufacture, the main body of the carburetor 1 is a one-piece structure including the fuel bowls 2 and 3 and a mixture conduit 4. The usual throttle body is omitted to save space, and the throttle shaft 75, carrying throttle 80, is journaled between the fuel bowls 2 and 3. The air horn 5 forms a continuation of the mixture conduit 4, and includes the integrally cast float bowl cover 6 secured to the main body 1 by a series of screws 7. Choke valve 81 is carried on shaft 82 journaled in the walls of the air horn 5.

As shown in Fig. 3, fuel enters the float bowls 2 and 3 by way of a nipple 9 having an integrally formed needle valve seat 10. Needle valve 11 controls the entrance of fuel through the nipple 9, and is urged against its seat 10 by the buoyancy of floats 13 and 14 shown in Figs. 1 and 5. Each float is supported on an arm which is similar in construction. Only one will be described, since a description of one will serve for both. For example, float 14 is supported on an arm 16 (Figs. 1, 3 and 5) which has a vertical leg 17 apertured to receive the hinge pin 19 forming one bearing for hingedly supporting the float 14. The other bearing for the hinge, indicated as 20 in Fig. 3, is spaced by an offset portion of the arm 17 indicated as 21, which extends parallel with the hinge pin 19. Each offset 21 has an integrally formed finger 22, which fingers are located side by side in a position to engage the needle valve 11 as the floats rise.

This arrangement of parts provides for individual control of the fuel level by the separate floats 13 and 14, so that fuel level may be accurately controlled, regardless of the tilt angle of the carburetor to either side.

Figs. 1 and 3 illustrate the mounting of the hinge pin 19. Opposite sides of the fuel bowl have opposed slots 26 and 27 receiving the ends of the hinge pin 19. A bail 28 has opposite ends disposed within the slots 26 and 27 and its intermediate portion engaged by the float bowl cover 6. This secures the pin 19 against vertical move-

2

ment within the slots 26 and 27, and holds the pin 19 stationary.

The fuel bowls 2 and 3, as best shown in Fig. 5, have shallow extensions such as 31 and 32 located on opposite sides of the mixture conduit 4. In Fig. 4, the extension 31 has been shown in dotted lines. These shallow chambers 31 and 32 have their lower surface normally disposed at approximately the fuel level within the fuel bowls 2 and 3. When the carburetor is tilted one way or the other about an axis transverse of the fuel bowls 2 and 3, the fuel will run in or out of the shallow chambers 31 and 32. If the tilt angle is forward, or to the left, as in Figs. 1 and 5, the shallow chambers 31 and 32 will receive enough fuel to maintain the fuel level in the fuel bowl at a level below the tip of the fuel nozzle. The carburetor will then continue to operate normally when tilted in this direction. If, on the other hand, the carburetor is tilted from the horizontal rearwardly, the shallow chambers are dry and do not add to or increase the fuel level in the main fuel bowls 2 and 3.

Main nozzle system

The main fuel system, including the main nozzle 37, is best shown in Figs. 1 and 2. Within the mixture conduit 4 is a main venturi 35 and a primary venturi 36.

Main fuel nozzle 37 extends into the primary venturi 36 from a main supply passage 38. The upper end of supply passage 38 is vented to the mixture conduit at 39 through a small vent tube 40 extending below the entrance to the main fuel nozzles 37. The lower end portion of passage 38 is offset to one side of throttle shaft 75 to save space vertically. Fuel is supplied to the main fuel supply passage 38 through a pair of metering orifices 42 and 43, both of which receive stepped metering rods. Metering rod 44 in orifice 42 is mechanically connected to be actuated by the throttle valve of the carburetor. The particular mechanism for operating rod 44 will be hereinafter described.

Metering rod 46 has an end portion bent at right angles received within a hole 47 in step-up piston 48. Cylinder 49 containing the piston 48 is connected to the mixture conduit 4 posterior of the throttle by way of passages 50 extending to a port (not shown) positioned below the throttle. A spring 53 within the cylinder 49 urges the piston 48 to its uppermost position, which is limited by a diaphragm or gasket 54 secured beneath the removable dust cap 55.

The parts of the main metering structure are so arranged that opening of the throttle moves the rod 44 downwardly so as to increase the flow through the metering orifice 42. Metering orifice 43 acts as an economizer and as a mixture step-up at higher manifold pressures when spring 53 is permitted to expand by decreasing suction on the piston 48. Bleed tube 40 projects into the main supply passage 38 to a point below the entrance of the main fuel nozzle 37, so that, during action of the main fuel system, the solid fuel flowing to the main nozzle will be broken into an emulsion by the addition of a jet of air from the nozzle bleed tube 40.

Idle fuel system

The system for supplying fuel to the engine within the low range of engine speed is best shown in Figs. 2 and 4. In the idle system is a diagonally extending passage 59 containing an idle tube 60 having a flange 61 seated as at 62 at the upper end of the passage 59. In the bowl cover is an offset passage 63 for connecting the passage 59 to vertical passage 64 containing metering orifice 65. As shown in Figs. 4 and 5, passages 59 and 63 extend around the mixture conduit 4 so that the idle system and main nozzle supply system are arranged side by side. Port 66 in the side of passage 64 opens into the mixture

conduit 4 slightly anterior of the throttle valve. A second port 67, controlled by a metering screw 68, connects by way of passage 69 to a second port 70 posterior of the throttle valve.

Accelerating pump

Located between and within the fuel bowls 2 and 3 is a cylinder 71, best shown in Fig. 3. A piston 72 in the cylinder 71 has a mounting stem 73 extending through the float bowl cover 6. At its upper end, the stem 73 has a flat 74, which terminates in abrupt, spaced shoulders.

Connected with the throttle shaft 75 is a short lever 76 having a pin 77 at its outer end. A link 78 having a slotted lower end receiving the pin 77 extends through a slot 79 (Fig. 5) formed in a raised boss within the fuel bowls 2 and 3, and also through a suitable slot in the float bowl cover 6 under dust cap 55. The connection between the throttle shaft 75 and link 78 is such that opening movement of the throttle 80 causes downward movement of the link 78.

As best shown in Fig. 1, the upper end of link 78 has a pair of arms 82 and 83, the latter of which is connected to the metering rod 44 by spring clip 84. Opposite arm 82 is received between the spaced shoulders of the machined flat 74 on the pump stem 73. Surrounding the stem 73 is a compression spring 86 constantly urging the piston 72 downwardly.

The structure above described will maintain the piston 72 in its upper position, compressing the spring 86 when the throttle valve 80 is closed. Opening movement of the throttle 80 permits expansion of the spring 86, forcing the piston 72 downwardly. Because of the lost motion connection between the arm 82 and the stem 73, the rate of descent of the piston is independent of throttle movement.

On downward movement, the fuel trapped below the piston 72 is forced outwardly through a discharge passage 90 controlled by a check valve 92. As shown in Fig. 3, the passage 90 opens at the top of the boss which contains the slot 79 for the throttle lever 78. When the float bowl cover 29 is in place, this passage is closed, as shown in Fig. 3. Check valve 92 is maintained in position by a U-spring 94 in the top of the passage 90.

Fuel passing the check valve is discharged through a nozzle 96 which is completely within the float bowl as shown in Figs. 3 and 5. A passage 97 connecting between the float bowl and the mixture conduit 4 is located in direct alignment with the nozzle 96, so that fuel discharged under substantial pressure will pass through the passage 97 into the mixture conduit 4. On the other hand, any leakage from the nozzle 96 will simply return to the float bowl. The location of the discharge nozzle 96 has the added advantage that it is exposed to substantially atmospheric pressure, and not the action of suction within the mixture conduit 4. Any suction which exists at the discharge end of the passage 97 merely creates a circulation within the mixture conduit, since the passage has an atmospheric bleed 95, as shown in Fig. 3.

Certain structures have been described herein which will fulfill all the objects of the present invention, but it is contemplated that other modifications will be obvious to those skilled in the art which come within the scope of the invention as defined by the appended claims.

I claim:

1. A carburetor for an internal combustion engine having a mixture conduit therein, comprising a fuel reservoir in said carburetor, a rotatable throttle shaft journaled in the walls of said carburetor transverse said mixture conduit, a throttle valve mounted on said throttle shaft, venturi means in said mixture conduit anterior to said throttle valve, a main fuel supply system in said carburetor for discharging fuel from said fuel reservoir to said mixture conduit adjacent said venturi means in response to engine demands, an idle fuel supply system in said

carburetor for discharging fuel from said fuel reservoir to said mixture conduit anterior and posterior of said throttle valve when said throttle valve is substantially closed, a metering rod in said carburetor for regulating the amount of fuel passing from said fuel reservoir to said main fuel supply system, an accelerating pump having a piston mounted in a cylinder in said carburetor for reciprocal movement therein, means for charging said cylinder with fuel from said fuel reservoir upon movement of said piston in one direction, means for discharging fuel from said cylinder into said mixing conduit upon movement of said piston in the other direction, a piston rod affixed to said piston, a biasing spring circumferentially disposed about said piston rod urging said piston in said discharging direction, stops formed by a recess in said piston rod in the direction of said reciprocal motion, an actuating member affixed at one end to said throttle shaft and mounted in said carburetor for reciprocal movement along an axis generally parallel to the axis of reciprocal movement of said piston rod and said metering rod, a transverse arm affixed to the other end of said actuating member, said transverse arm having one end thereof operatively connected to said metering rod and the other end thereof having a portion smaller than the spacing between said stops and received between said stops of said piston rod, whereby said actuating member and said metering rod and said piston rod are operatively connected together.

2. A carburetor for an internal combustion engine having a mixture conduit therein, comprising a fuel reservoir in said carburetor, a rotatable throttle shaft journaled in the walls of said carburetor transverse said mixture conduit, a throttle valve mounted on said throttle shaft, venturi means in said mixture conduit anterior to said throttle valve, a main fuel supply system in said carburetor for discharging fuel from said fuel reservoir to said mixture conduit adjacent said venturi means in response to engine demands, an idle fuel supply system in said carburetor for discharging fuel from said fuel reservoir to said mixture conduit anterior and posterior of said throttle valve when said throttle valve is substantially closed, a metering rod in said carburetor for regulating the amount of fuel passing from said fuel reservoir to said main fuel supply system, an accelerating pump having a piston mounted in a cylinder in said carburetor for reciprocal movement therein, means for charging said cylinder with fuel from said fuel reservoir upon movement of said piston in one direction, means for discharging fuel from said cylinder into said mixing conduit upon movement of said piston in the other direction, a piston rod affixed to said piston, a biasing spring circumferentially disposed about said piston rod urging said piston in said discharging direction, stops formed by a recess in said piston rod in the direction of said reciprocal motion, an actuating member affixed at one end to said throttle shaft and mounted in said carburetor for reciprocal movement along an axis generally parallel to the axis of reciprocal movement of said piston rod and said metering rod, a transverse arm integral with the other end of said actuating member, said transverse arm having one end thereof operatively connected to said metering rod and the other end thereof received between said stops of said piston rod, whereby said actuating member operatively urges said piston rod in a direction to charge said cylinder with fuel.

3. A carburetor for an internal combustion engine having a mixture conduit therein, comprising a fuel reservoir in said carburetor, a rotatable throttle shaft journaled in the walls of said carburetor transverse said mixture conduit, a throttle valve mounted on said throttle shaft, venturi means in said mixture conduit anterior to said throttle valve, a main fuel supply system in said carburetor for discharging fuel from said fuel reservoir to said mixture conduit adjacent said venturi means in response to engine demands, an idle fuel supply system in

in said carburetor for discharging fuel from said fuel reservoir to said mixture conduit anterior and posterior of said throttle valve when said throttle valve is substantially closed, a metering rod in said carburetor for regulating the amount of fuel passing from said fuel reservoir to said main fuel supply system, an accelerating pump having a piston mounted in a cylinder in said carburetor for reciprocal movement therein, means for charging said cylinder with fuel from said fuel reservoir upon movement of said piston in one direction, means for discharging fuel from said cylinder into said mixing conduit upon movement of said piston in the other direction, a piston rod affixed to said piston, a biasing spring circumferentially disposed about said piston rod urging said piston in said discharging direction, stops formed by a recess in said piston rod in the direction of said reciprocal motion, an actuating member affixed at one end to said throttle shaft and mounted in said carburetor for reciprocal movement along an axis generally parallel to the axis of reciprocal movement of said piston rod and 20 said metering rod, a transverse arm integral with the other end of said actuating member, a fastener operatively

connecting said transverse arm at one end thereof to said metering rod, and the other end of said transverse arm received between said stops of said piston rod, whereby said actuating member operatively urges said piston rod 5 in a direction to charge said cylinder with fuel.
